COIN CONTROLLED MECHANISM

Application filed August 2, 1928. Serial No. 297,018.

My invention relates to improvements in coin controlled mechanisms designed particularly, though not exclusively, for vending devices of the character disclosed in my co-pending application Serial Number 24,132, from which this application has been divided.

An object of this invention is to provide a simple, durable and relatively inexpensive mechanism of the instant nature for a device 10 wherein dual dispensers are operated by a single actuator and caused alternately to vend boxes or like packets.

Another object of the invention is to provide a mechanism of the present kind, where- 15 by the associated vending device is normally locked against actuation, but freed to function upon the application of the proper coin thereto.

A further object is to supply a coin con- 20 trolled mechanism including an actuating lever arranged to guard the coin slot in all except the extreme positions of the actuating lever, wherein the slot is cleared to receive a coin preparatory to the initiation of move- 25 ment of said lever.

With the foregoing and other objects in view, which will appear in the following description, the invention resides in the novel combination and arrangement of parts and in 30 the details of construction hereinafter described and claimed.

In the drawings, Figs. 1 is a perspective view of a vending machine fitted with my improved coin controlled mechanism; Fig. 2 is 35 a fragmentary elevational view of the coin controlled mechanism proper, the cover plate being shown in connection therewith; Fig. 3 is a cross sectional view taken as on the line 3—3 of Fig. 2; Fig. 4 is a perspective view 40 of the coin mechanism proper as seen in inverted position; Figs. 5 and 6 are bottom views of the coin mechanism proper, a coin of proper size being shown in Fig. 5 and a coin of improper size being shown in Fig. 6, and 45 Fig. 7 is a detail perspective view of the dual coin embracing yoke.

Referring to the drawings, it will be observed that the illustrated vending machine includes a box-like base A and a tower-like 50 structure B, the box-like base being equipped

with an upper frame-plate 11. A front plate 12 secured at its upper edge to the upper frame-plate 11 and at its lower edge to a lower or bottom frame-plate (not shown) constitutes the front of the base A. Side plates 13 attached to the upper and lower frame-plates are formed with riser portions 13' at the rear thereof, said riser portions being integral with a deck-plate 15. The back 55 of the base A is fitted with a door (not shown) having a suitable lock for holding the same closed. The tower-like structure B includes a sheet metal body stamped to form a pair of spaced magazines or chutes 19. The front panels of the magazine have eight openings 25 stamped therein, the lower edges of said panels lying in the horizontal plane of the deck-plate 15 of the base A.

At the bottom of each magazine 19 is a combination vending device C each forming 70 a box support and vending tray. These vending devices are identical, each being formed from a strip of sheet metal bent to provide a base-plate 26, an elevated rest 27 at the rear of the device and an upright guard flange 28 75 at the front of the device. In the retracted position of a vending device C, the box rest 27 is disposed beneath the deck-plate 15, the tray portion between said rest 27 and the front guard flange 28 being then sheathed 80 within the magazine to receive the lower-most box or packet of the stack therein. The forward projection of said device from said retracted position results in shifting the box rest 27 under said stack of packets and in 85 unsheathing said tray portion of said device to permit of the removal of the contained packet therefrom. A lever 31 is pivoted to the upper frame-plate 11, the forward end of said lever overreaching the front of the base 90 A and providing a convenient handle 31^a for swinging the lever. By means of connecting links (not shown) between lever 31 and the vending device C, which links embody a part 95 of the subject matter of my said copending application, the said devices C are caused alternately to be retracted and projected upon the swinging of the lever 31 from side to side. In the extreme positions of the lever 31 one vending device C is retracted and the 100

other projected, while, in the intermediate position of said lever, both devices are to be found in retracted position. In other words, the first half stroke of the lever 31 in one direction retracts the previously projected vending device C, while the last half stroke of said lever in the same direction projects the other vending device C.

Coin controlled latching device D is associated with the lever 31 to prevent the vending of packets from the machine except upon the application thereto of a coin of proper size.

This device proper comprises a cage formed of sheet metal and consisting of opposed top flanges 31 and 32 from which depend forward and rear walls 33 and 34, said walls being slightly spaced apart to form between them a coin slide open at top and bottom and extending transversely of the lever 31. The flanges 31 and 32 are seated within a depression in upper frame-plate 11, the depending walls 33 and 34 occupying a slot formed in said plate 11 (Fig. 3). The blank from which the cage is constructed is provided with tie members 35 serving to join and relatively space the walls 33 and 34 at their lower margins and is further provided with clip members 36 issuing from the ends of wall 34 and, when bent over the end margins of wall 33, as shown, serving also to tie and relatively space said walls 33 and 34. A dual coin embracing yoke or traveler d (Fig. 7) is provided, the same including a block 37 slideable lengthwise on flange 31, said block being formed with a pair of outer depending branches or fingers 38 and an intermediate branch or finger 39. A pin 40 fixed medially of the block 37 fits within a slot 41 in the lever 31 and serves to connect said block 40 with said lever 31. The fingers 38, 39, depending from said block 37, extend into the way or slide between the walls 33, 34 of the coin cage. Reaching into the coin slide through an opening 42 in the rear wall 33 of the cage are a plurality of spring pressed tumblers 43. The opening 42 is formed by cutting away a medial marginal portion of wall 33 and by bending back portions of said wall as at 44 and 45, portions 44 forming guide flanges for the extreme tumblers 43. These tumblers are pivoted on a common hinge-pin 46 mounted at its ends in ears 47 turned outwardly from wall 33. Each tumbler 43 includes a head portion 48 through which the hinge-pin 46 extends and further includes a body portion 49, which normally occupies position within the coin slot between the walls 33 and 34, the forward edge of the body portion 49 being yieldingly held against the front wall 34 by the action of a spring 50 interposed between the flange 31 and the head portion 48 of the tumbler. Except for the extreme tumblers, the tumblers 43 are identical, said extreme tumblers differing from the others in that

respect best seen in Figs. 4, 5 and 6, where, it will be observed, inner marginal faces of the bodies thereof are ground down to reduce the same in thickness. The yoke fingers 38, 39 are spaced apart so that one terminal finger 38 and the intermediate finger 39 will embrace the extreme tumblers 43 in either of the extreme positions of the lever 31. A cover plate 51 superimposing the block 37 has a slot 52 therein in which the pin 40 on block 37 may play and is further provided with a slot 53 for coins. Thus formed with said coin slot 53, the cover plate constitutes a coin guide through which coins may be inserted into position between branches of the traveler yoke d and between wall 34 on the one side and wall 33 and tumblers 43 on the other side. This coin guide, however, is unobstructed by the lever 31 only when said lever is in one of its extreme positions (Fig. 1). In either of such positions of the lever 31, a proper coin inserted into the coin slot 53 passes between the medial yoke finger 39 and one of the terminal fingers 38. Thus disposed the coin engages and swings all of the tumblers 43 rearward (Fig. 5) and in so retracting said tumblers, causes the way between the walls 33, 34 to be cleared for the passage therewith of the yoke finger 39. As the lever 31 is swung to actuate its associated mechanism, the tumblers 43 progressively enter the coin slide behind the intermediate yoke finger 39 and thereby lock said lever against reversal at various steps in either operating throw thereof. In being pushed past the tumblers 43 by the yoke finger 39, a coin holds said tumblers retracted until they are progressively overreached by said finger, the coin being finally thrust sidewise beyond the last tumbler, whence it falls from between the walls 33, 34 of the cage to the coin box therebeneath. While the coin slot 53 in the cover plate 51 does not prevent the insertion into the device of an undersized coin, it does prevent the insertion of an oversized coin. If an undersized coin is inserted through the coin slot 53, the extreme tumblers 43 are undisturbed by the entry of the small coin (Fig. 6) and consequently continue to secure the traveler yoke d immovable under any force that may be applied to the lever 31. By grinding down the inner margins of the extreme tumbler bodies 49 and thereby reducing the thickness thereof, I guard against the possible actuation of the device by the use of coins or slugs departing in the slightest from the proper diameter. When it occurs that an undersized coin has been inserted through the coin slot 53, no harm or inconvenience is experienced in respect to the device, since upon the next insertion of a proper coin, the previously inserted and ineffective coin is thrust downwardly by the proper coin out of the grasp of the tumblers 43, when it falls into the coin receiver.

While the grasping of a proper coin between the tumblers 43 and the front wall 34 is ordinarily sufficient to keep it from falling through as the traveler yoke *d* is shifted to its 5 limit of movement, I provide a precautionary measure against tampering users, which consists in slightly turning or burnishing the edge of wall 34 toward the tumblers 43 and thereby forming on said wall a flange 54.

10 This aids in guiding a proper coin sidewise past the tumblers, without interfering with the downward expulsion of an undersized coin.

To reinforce the wall 33 where it is weakened in forming the opening 42 to receive the bodies 49 of the tumblers 43, I employ two U-shaped strengthening clips 55, which embrace the walls 33 and 34, the latter at positions adjacent to said opening 42. To 20 accommodate the clips 55 in releasing coins from the bottom of the coin slide, I cut away the corners of the fingers 38, as at 59, whereby the coins may roll from said clips free of said fingers 38.

25 My improved coin control device is advantageous because of its efficiency, simplicity and durability. It is particularly, though not exclusively, adapted for use in connection with vending machines and the like embodying a reversible actuator operating upon each throw to actuate its associated mechanism.

Changes in the specific form of my invention, as herein disclosed, may be made within the scope of what is claimed without departing 35 from the spirit of my invention.

Having described my invention, what I claim as new and desire to protect by Letters Patent is:

1. The combination with a reversible actuator for operating an associated device upon either stroke of the actuator, of a coin controlled mechanism for said actuator including a cage embodying spaced front and rear walls forming a coin slide, a group of tumblers hinged 40 to the cage, the bodies thereof being adapted to swing into and out of the coin slide, each tumbler having individual means for yieldingly holding the same with the body thereof in position within the coin slide, a dual coin embracing yoke connected with said actuator and comprising two end fingers and an intermediate finger, all movable in said slide, the intermediate finger and one end finger being adapted closely to embrace the group of 45 tumblers within the coin slide, a guide for directing a tumbler retracting coin into the coin slide between the tumblers and the front wall, the lower edge of said front wall opposite the tumblers having a flange thereon turned in the direction of said tumblers, said tumblers, when retracted by a coin overreaching the group thereof, offering no obstruction to the intermediate finger, but acting progressively to enter behind said finger.

50 55

2. The combination with a reversible actuator for operating an associated device upon either stroke of the actuator, of a coin con-

trolled mechanism for said actuator including a cage embodying spaced front and rear walls forming a coin slide, the rear wall having a marginal opening therein, a group of tumblers hinged to the cage, the bodies thereof being adapted to swing into and out of the coin slide through said opening, each tumbler having individual means for yieldingly holding the same with the body thereof in position within the coin slide, the bodies of the extreme tumblers being cut away at their inner faces, a dual coin embracing yoke connected with said actuator and comprising two end fingers and an intermediate finger, all movable in said slide, the intermediate finger and one end finger being adapted closely to embrace the group of tumblers within the coin slide, a guide for directing a tumbler retracting coin into the coin slide between the tumblers and the front wall, the lower edge of said front wall opposite the tumblers having a flange thereon turned in the direction of said tumblers, said tumblers, when retracted by a coin overreaching the group thereof, offering no obstruction to the intermediate finger, but acting progressively to enter behind said finger.

3. The combination with a reversible actuator for operating an associated device upon either stroke of the actuator, of a coin controlled mechanism for said actuator including a cage embodying spaced front and rear walls forming a coin slide, the rear wall having a marginal opening therein, a group of tumblers hinged to the cage, the bodies thereof being adapted to swing into and out of the coin slide through said opening, each tumbler having individual means for yieldingly holding the same with the body thereof in position within the coin slide, the bodies of the extreme tumblers being cut away at their inner faces, a dual coin embracing yoke connected with said actuator and comprising two end fingers and an intermediate finger, all movable in said slide, the intermediate finger and one end finger being adapted closely to embrace the group of tumblers within the coin slide, a guide for directing a tumbler retracting coin into the coin slide between the tumblers and the front wall, the lower edge of said front wall opposite the tumblers having a flange thereon turned in the direction of said tumblers, said tumblers, when retracted by a coin overreaching the group thereof, offering no obstruction to the intermediate finger, but acting progressively to enter behind said finger.

4. A coin controlled mechanism for a reversible actuator including a cage forming a coin slide, tumbler means adapted to swing into and out of the coin slide, said means being yieldingly held in position within the coin slide, a dual coin embracing yoke adapted to be connected with said actuator and comprising two end fingers and an intermediate finger, all movable in said slide, the

intermediate finger and one end finger being adapted closely to embrace the extremities of said tumbler means within the coin slide, a guide for directing a tumbler retracting coin 5 into the coin slide, the yoke being movable in said slide in the presence of such coin.

5. A coin controlled mechanism for a reversible actuator including a cage forming a coin slide open along the bottom thereof, 10 a group of tumblers carried by the cage and individually normally projecting into the coin slide, a traveler adapted to be connected with the actuator and having a finger movable in said slide, said tumblers being adapted to be shifted and held out of the path of 15 said finger by means of an appropriate coin inserted in the coin slide, said tumblers acting progressively to reenter the path of said finger behind the same.

20. 6. The combination with an actuating lever of a coin controlled mechanism therefor, said mechanism including a coin slide, a coin embracing yoke attached to said lever, the branches of said yoke being movable in said slide, a guide for directing a coin into said slide and between said branches, tumblers associated with the slide and adapted to be held retracted by a coin introduced through said guide, said tumblers acting to obstruct 25 the movement of said yoke in the absence of a coin to retract said tumblers and to permit only of a progressive movement of said yoke in the presence of a tumbler retracting coin.

7. The combination with a reversible lever 30 for actuating an associated device upon one throw thereof in either direction, of a coin controlled mechanism for said lever, the same including a coin slide, a dual coin embracing yoke attached to said lever and comprising two end fingers and an intermediate finger, 35 all movable in said slide, a guide for directing a coin into said slide, tumblers associated with the coin slide, all adapted to be retracted by a proper coin introduced through said guide, said tumblers serving progressively to 40 obstruct the intermediate finger of said yoke against reversal upon movement of said lever in either direction.

8. A coin controlled mechanism for an actuating device comprising a slide for the movement therein of a coin normally endwise thereof, a traveler for association with the actuating device having a finger movable in the coin slide, tumblers projecting into the 55 coin slide, said slide being formed at one edge for the edgewise insertion thereinto of a coin and at the opposite edge for the expulsion of such coin, all of the tumblers being adapted to be retracted and held clear 60 of the way of the progressing finger by a coin of proper character, those of the tumblers not held retracted by the coin, if of improper character, serving through said coin to obstruct the movement of said finger.

9. A coin controlled mechanism comprising

ing a slide for the movement therein of a coin normally endwise thereof, tumblers normally projecting into the coin slide, a traveler having a finger disposed in the slide, said slide being formed at one edge for the edge- 70 wise insertion thereinto of a coin and at the opposite edge for the expulsion of such coin, some or all of the tumblers, according to the character of the coin used, being adapted to be retracted by the coin upon its insertion into the slide, the finger being movable only to push the coin past the tumblers held retracted by the coin.

10. A coin controlled mechanism comprising a coin slide formed for the insertion 80 thereinto of a coin, tumblers normally projecting into the coin slide, a traveler having a finger disposed in said slide, some or all of the tumblers, according to the character of the coin used, being adapted to be retracted by the coin upon its insertion into the slide, the finger being movable in one direction to push and follow the coin past those tumblers held retracted by the coin, said tumblers being adapted to be progressively 85 re-projected into the slide at the rear of said finger and thus progressively block the movement of the finger in the reverse direction.

11. A coin controlled mechanism for an actuating device including a cage forming a 90 coin slide, a multiplicity of tumblers arranged side by side in an assembly lengthwise of the coin slide and individually normally projecting into said slide, a traveler associated with the actuating device and having a finger projecting into and movable along the coin slide, said tumblers, or some of them, by the contact therewith of a coin inserted into the slide, being adapted to be 95 retracted and held out of the path of the finger, said finger being movable endwise of the tumbler assembly in a direction in which all of the advance tumblers are withheld from its path, said tumblers being adapted progressively to re-assume positions with 100 in the slide at the rear of the moving finger, thus preventing the movement of said finger in a reverse direction.

In testimony whereof, I have signed my name to this specification.

MARTIN BOHLIG.
